R. E. STURMAN

VALVE

Filed Dec. 4, 1922

Inventor

ROBERT E. STURMAN

By *Robert E. Sturman*

Attorney

UNITED STATES PATENT OFFICE.

ROBERT E. STURMAN, OF MINNEAPOLIS, MINNESOTA.

VALVE.

Application filed December 4, 1922. Serial No. 604,722.

To all whom it may concern:

Be it known that I, ROBERT E. STURMAN, a citizen of the United States, residing at Minneapolis, in the county of Hennepin 5 and State of Minnesota, have invented certain new and useful Improvements in Valves, of which the following is a specification.

This invention relates to valve structures 10 and the main object is to provide an improved type of valve wherein a fluid under pressure and communicating with the valve will open the latter for passage of the fluid only when said pressure has reached a pre- 15 determined degree of strength, and wherein said valve will only close said passage when such predetermined pressure is materially reduced, so that neither the pressure pro- 20 ducing means nor the size of the valve open- 25 ing will be materially affected by the normal tendency of the valve to close or react against the pressure current which has opened it.

A further, or probably a more specific, 30 object is to provide a valve structure in combination with a fluid conduit, which delivers the fluid from a source under pressure to a supply tank, whereby when the tank is full the surplus fluid will open the valve so that it may be discharged into an auxiliary or 35 second tank in such a manner as to not subject the initial pressure or power to the additional labor of holding the valve open against spring or gravity resistance as is 40 usually required. Further objects will be disclosed and described in the course of the following specification and are embodied in the device illustrated in the accompanying drawings wherein:

Fig. 1 is an elevation of the device showing the main valve structure in diametrical section, and the passage therein open.

Fig. 2 is a sectional detail view on the line 2-2 in Fig. 1.

Fig. 3 is a sectional detail on the line 3-3 in Fig. 1.

Referring to the drawings more specifically and by reference characters, 4 designates a T-coupling in which is secured a supply 50 pipe 5, a primary delivery pipe 6, and a nipple 7 on which is secured the valve body or casing 8. A secondary supply pipe 9 communicates with the nipple 7 (when the valve is open) through a port or seat 10, in

a partition 11 of the body member 8, and 55 a strainer 12. The valve closing element consists of a core or plug 13 which is slidably retained in a member 14 which is secured on the casing 8 by a nut 15. The lower end of the core 13 is provided with 60 a frusto-conical portion 15 which is adapted to fit into a correspondingly shaped seat in the partition 11, and is also provided with a straight portion 16 adjacent thereto which when the valve is shut or partially shut 65 slidably engages in the cylindrical part of the port 10. Thus the port passage is entirely closed until the part 16 has been raised its full length out of the cylindrical part of the port, which action is essential to the 70 hereinafter described valve mechanism.

The mechanism just referred to may, for 75 sake of convenience, be called a tripper; and consists primarily of a lever 17 having a channel in which rolls a ball 18. The lever 80 has an integral projection 19 which is pivotally secured, as at 20 to a bracket 21, which in turn is rotatably mounted and secured by a nut 22 on the member 14. The longer 85 and heavier end of the lever is held up by a pin 23, which is also pivotally secured to the lever projection 19 and rests with its lower end in a pocket 24 in the upper end of the member 13, said pocket being large enough to allow play for the pin to compensate for its swinging movement from 90 the center 20.

The short end of the lever is provided 95 with a set screw 25 against which the ball 18 rests, when in that end of the channel. The screw is threaded into the lever, and is provided with a lock nut 26, so that the position of the ball with respect to the tilting center (20) of the lever can be easily adjusted. The long end of the lever is provided with a rotatable bolt 27 which is threaded in and adjustably carries a bumper 28, which limits the rolling movement of the ball 18 in that direction. This bumper guides in a slot 29 in the lever 17. Thus 100 by turning the bolt 27 the position of the bumper may be regulated.

The operation and use of the device, as 105 thus described, will be explained by associating it with a type of water system for which it is particularly, but not necessarily, intended to be used. With this in mind it will be assumed that pipe 5 leads from a

windmill driven pump, pipe 6 leads to a primary tank and pipe 9 leads to a secondary tank or some other place where it is desired to divert the water after the primary tank is filled.

The valve is normally closed, the long end of the lever 17 being down, as indicated by the dotted lines in Fig. 1, the ball 18 being in its leftmost position. As the windmill 10 turns, either continuously or periodically the water is forced through the pipes 5 and 6 and to the primary storage tank. To this extent the valve is in no way affected as the pressure required to fill the tank is not 15 sufficient to raise the lever and open the valve. But when the primary tank has reached its capacity the reaction together with the usual current pressure will rush the water up into the valve, and will, by 20 raising the plunger 13 and lever 17, cause the ball 18 to roll down to the short end of the lever. And although the ball does not counter-balance or over-balance the heavier end of the lever it reduces the downward 25 pressure or resistance on the valve core to the extent that but a small current of water will hold it open. The object as well as the result of this arrangement will be quite obvious, for it will readily be seen that as the 30 valve will stay open almost of its own accord the windmill will not be required to work with any less efficiency than when filling the primary tank, which heretofore has been the case as most valves for this purpose have 35 been held open against strong resisting pressure solely by virtue of the current power.

Should the windmill or the pumping apparatus for any reason stop then the valve core 13 will immediately reseat itself, as the 40 weight of the longer end of the lever 17 slightly overbalances the shorter end even with the weight of the ball added. This will not only check a back current from the pipe 9 through the valve, but will also cause 45 the next flow of water to be directed to the primary tank in case that drawing off has reduced the pressure therein.

The necessary valve releasing and closing pressure can be adjusted to any degree desired by turning the screw 25, and the bolt 50 27, and also by changing the fulcrum of the lever, as provided for. It may here be noted that the bracket 21 is rotatably mounted on the member 14, so that the lever

can be swung to any convenient position 55 found necessary or desirable.

It is understood that suitable modifications in the general design and structural details of this invention may be made, provided, however, that such modifications come within the spirit and scope of the appended claims. Having now therefore fully shown and described my invention, what I claim to be new and desire to protect by Letters Patent is:

1. In a valve having a cylindrical port, a plunger or core slidably mounted in alignment with said port so as to engage therein during part of its movement, means for yieldingly keeping said core in engagement with the port, and automatic means for materially reducing the closing pressure on said plunger when the same has been removed from engagement with said port. 70

2. A valve having a vertically arranged cylindrical port, a plunger slidably mounted in alignment with and above the port for engagement therein during part of the movement of the plunger, a gravity actuated device for yieldingly pressing said plunger toward and into the port, means operable by lifting the plunger to vary the gravity pressure exerted thereagainst. 75

3. In combination with a valve having a port closing member, a lever mounted on the valve and operatively engaged with said member so as to yieldingly press the latter toward the port, a ball adapted to roll on said lever, when the latter is tilted, to its lowest end, said ball being of substantial weight so as to vary the gravitational pressure of the heavier end of the lever against said port closing member, and an adjusting device at one end of the lever for limiting the movement of the ball in that direction. 85

4. In combination with a valve having a port closing member, a bracket rotatably mounted on the valve, a lever pivoted on the bracket and operatively communicating with the member, said lever being heavier at one end to gravitationally effect a downward pressure on the member, and means, operative by an opening movement of the port closing member, to reduce the gravitational pressure mentioned. 100

In testimony whereof I affix my signature.

ROBERT E. STURMAN.
